UNITED STATES PATENT OFFICE.

ALBERT L. HALL, OF LOS ANGELES, CALIFORNIA, ASSIGNOR TO SIMPLEX HEATER COMPANY, OF LOS ANGELES, CALIFORNIA.

WATER-HEATER BURNER.

Application filed July 15, 1924. Serial No. 726,183.

To all whom it may concern:

Be it known that I, ALBERT L. HALL, a citizen of the United States, residing at Los Angeles, in the county of Los Angeles and State of California, have invented certain new and useful Improvements in Water-Heater Burners, of which the following is a specification.

My invention relates to burners and more particularly to water heater burners, and the general object thereof is to provide an improved automatic water heater burner which will be simple in construction, and positive and efficient in operation.

Other objects and advantages will be made manifest in the following specification for an embodiment of the invention illustrated in the accompanying drawing.

Referring to the drawing:

Figure 1 is a vertical longitudinal section of my burner, with the lower portion of the water heater shown in dotted lines.

Figure 2 is a horizontal section taken on line 2—2 of Figure 1.

Figure 3 is a plan view of the burner.

In the drawing 1 indicates a vertical cylinder in which is mounted a piston 2. The lower end of said cylinder is closed by a head 3 which is screw seated in said lower end of the cylinder as indicated at 4. The lower end of said cylinder is provided with a port 5 while the upper end of said cylinder is provided with a port 6. A stuffing box 7 is provided at the upper end of the cylinder 1, which stuffing box comprises a cup-shaped receptacle 8, a packing 9 and a gland 10 which is screw seated in the upper end of said receptacle. The receptacle 8 is formed integral with the upper head 11 of the cylinder 1 with its lower half depending below said head within the cylinder and with its upper half projecting above said cylinder head.

A tubular housing 12 is formed with a lower ring-shaped end member 13, a gas chamber 14 located a short distance above said ring member, a gas inlet 15 in the upper end of said chamber and a needle valve casing 16 opposite said inlet, the ring shaped member 13 being joined to the gas chamber 14 by a semi-cylindrical wall 17 at the rear side of the member and chamber, leaving the front of the housing open between the upper end of the member 13 and the lower end of the chamber 14 as indicated at 18, to permit

access to the gland 10, the head of which gland being located in the space 19 between said member and chamber.

A rod 20 is adjustably connected at its lower end to the piston 2 and extends upwardly through the stuffing box 7 and into the chamber 14, the piston being provided with a central opening 21 through which the lower end of the rod extends and there being nuts 22, 23 and 24 seated on a thread 25 on the lower end portion of the rod, the nuts 22 and 23 engaging respectively the upper and lower sides of the piston wall 26 and the nut 24 engaging and locking the nut 23. A packing ring 27 fits on the piston rod 20 in the bottom of the chamber 14 and a pair of disks 28 and 29 fit loosely on the rod, the disk 28 resting upon the packing ring 27. A gas valve 30 is screw seated on a thread 31 on the upper end of the piston rod 20 and a spring 32 surrounds the piston rod, bearing at its lower end upon the disk 28 and at its upper end against the disk 29, which latter disk is held by the spring 33 against the upper side of the valve 30.

A head 35 is screw seated in the upper end of the chamber 14 as indicated at 36, said head having a bore 37 in its lower side in the upper end of which is fitted a valve seating ring 38 against which seats the gas valve 30. The head 35 is formed with an upwardly projecting cylindrical fuel receptacle 39 the lower wall of which is provided with an opening 40 in communication with the opening 41 in the center of ring 38. The upper end of the receptacle 39 is closed by a disk 42 provided with a central aperture 43. The head 35 is formed with an external annular flange 44 which nests upon the upper end of the chamber 14.

A tubular jet 45 is fitted at its lower end over the upper portion 46 of the body of the head 35 with the lower edge of the jet resting upon the flange 44 of said head. Air inlets 47 are provided in the lower portion of the jet 45 opposite the fuel receptacle to supply the gas escaping from the aperture 43 with oxygen to support combustion. The upper end or nozzle 48 of the jet 45 is formed with a plurality of nozzle members 49, which, in cross section, extend radially from the center of the jet, the conduits 50 of said nozzle members converging upwardly, as indicated at 51, and inclining outwardly from the tubular wall 52 of the jet, as indicated at 53.

cated at 53, and terminating in elongated radial outlet slots 54 in the extremities of the nozzle members. The formation of the burner nozzle into a plurality of nozzle members provided with elongated outlet slots and the convergence of the nozzle conduits to said slots provides a jet having maximum outlet area with means for effecting a maximum concentration of the fuel for combustion, whereby combustion takes place in a blue flame of maximum volume and heat intensity. A screen 55 is placed across the inside of the jet 45 at the base of the nozzle 48 to prevent back firing of the flame into the upper end of the jet mixing chamber 56 below the screen. A deflector 57 surrounds the jet 45, being secured to the jet by a set screw 58, and extends downwardly and outwardly from the jet to a plane substantially coincident with the center of the air inlets 47, which deflector prevents back firing of the flame around the outside of the jet and through the air inlets 47 into the mixing chamber 56.

25 A pilot burner 60 comprises the valve casing 16, gas inlet port 61 in said casing leading from the housing 14 opposite the gas inlet 15, a needle valve 62 in said casing controlling said port, an outlet port 63 in said casing and a burner tube 64 leading from said outlet port to the upper end of the nozzle 48.

30 The gas inlet port 15 is connected to a gas supply pipe 65. A water conduit 66 is connected at one end to the cylinder port 6 and at its other end to an imperfect leaky check valve 67. A pipe 68 is connected at one end to said check valve and at its other end to one end of an elbow 69, the other end of said elbow being connected to one end of a water heater coil 70 and the other end of said coil being connected to the water heater tube 71. The cold water supply pipe 72 is connected to the corner of the elbow 69.

35 A bypass 73 is connected to the outlet port 5 and to the water heater valve 74 which is connected to the outlet end of the water heater tube 75. The hot water pipe 76 leads from the valve 74.

40 The operation of my burner is as follows: Normally the needle valve 62 is open and the pilot burner 60 lighted at the upper end of the burner tube 64. Water enters both ends of the cylinder 1 through ports

5 and 6 but the piston 7 is held in its uppermost position and the valve 30 held closed on its seat by the spring 32, which overcomes the balance in water pressure in the lower and upper ends of the cylinder. When water is drawn from the heater through pipe 76, the water in the lower end of the cylinder 1 escapes through the port 5 and the bypass 73, and additional water restricted by the leaky valve 67, enters the upper end of the cylinder through the port 6 and slowly forces the piston 7 downwardly and slowly opens the valve 30 so that the gas will pass gradually from the port 15 through the ports 41 and 40, the receptacle 39 and port 43 into the mixing chamber 56 and out through the burner conduits 50, without blowing out the pilot light, whereupon said light will ignite the gas passing from the burner through said conduits. When the valve controlling pipe 76 is closed water again passes through the bypass 73 and the port 5 into the lower end of the cylinder 1, and restores the balance of pressure in the cylinder, whereupon the spring 32 overcomes said balance raises the piston 7 and closes the valve 30, thus shutting off the burner.

45 A conical projection 80 is formed on the face of the valve 30 which projects into the opening 41 of the valve seating ring 38 and prevents said opening from being closed by the compression of the ring by the valve 30 under the influence of the spring 32.

The piston 2 has a peripheral groove 81 in the lower side of which is fitted an expandable metal packing ring 82, there being a packing 83 in the groove above said ring. The ring 82 expands against the interior of the cylinder 1 and prevents the packing from being forced by the water pressure below the piston between the piston and cylinder.

50 Having thus described my invention what I claim is:

In a burner, a soft valve seating ring, a gas valve means for normally closing said valve under pressure, and a projection projecting into the opening of said ring to prevent closing of said opening by the pressure of the valve against the ring.

55 In testimony whereof I affix my signature.

ALBERT L. HALL.
